TRAVELING WAVE TUBE

Frederick L. Washburn, Jr., Altamont, N.Y., assignor to
General Electric Company, a corporation of New York

Application June 28, 1956, Serial No. 594,456

16 Claims. (Cl. 315—3.5)

This invention relates to traveling wave tubes and more particularly to improvements in traveling wave tubes adapted for operation at high power levels.

A type of traveling wave tube in common use heretofore, includes a cathode for providing a source of electrons, means for forming the electrons into a beam and means for directing the electron beam axially through a helix, or other type slow-wave structure and input and output coupling means disposed near the ends of the helix. Glass rods or tubing space the helix away from the walls of an outer glass tubing and support it centrally about the path of the electron beam. When the traveling wave tube is used as an amplified, attenuating material in the form of graphite coating may be disposed on the rods or tubing.

Traveling wave tubes of the above type have heretofore been provided for amplification at relatively low power levels. I have found that, before such traveling wave tubes can be utilized for operation at high power levels and at high frequencies, for example, to provide outputs in the order of 100 watts at 3,000 mc., various features of the tube have to be improved in order to render the tubes efficiently operable under these conditions. For high power levels and high frequency operation, a sharply defined and uniform cross section beam is required. The beam must be accurately aligned with respect to the helix, and means must be provided for dissipating the heat energy developed in the helix. Although the description hereinbelow is directed particularly to a helix, other types of slow-wave transmission line structures could be satisfactorily employed.

It is, accordingly, a principal object of the present invention to provide a traveling wave tube adapted for operation at high power levels.

It is another object of the present invention to provide a traveling wave tube including novel beam forming and controlling means whereby said tube is more efficiently operable at high power levels.

It is another object of the present invention to provide an improved heater for cathodes of traveling wave tubes.

It is another object to provide an improved slow wave structure comprising a helix having improved heat radiating means associated therewith.

In the attainment of the foregoing objects of my invention, I provide, in a traveling wave tube, means for accurately aligning a helix with the axis of the electron beam. The helix consists of a ribbon-like metallic material and is supported by a quartz tubing. A coating of a carbon suspension is applied to the helix for purposes of radiating heat energy. Further, I provide a toroidal coil heater for the cathode, which heater coil is self-supporting and wound such as to minimize external magnetic fields developed by said heater to avoid deleterious effects of such fields on the beam.

Other objects and advantages will become apparent after a consideration of the specification and drawings in which:

2

Figure 1 is a schematic view of a traveling wave tube embodying features of my invention;

Figure 2 is an enlarged cross sectional view taken along lines 2—2 of Figure 1;

5 Figure 3 is an enlarged plan view showing a toroidal heater according to the invention;

Figure 4 is a fragmentary enlarged view partly in cross section of a helix in accordance with my invention;

10 Figure 5 is a fragmentary enlarged view partly in cross section showing the cathode-aligning method and apparatus in accordance with my invention; and

Figure 6 is an exploded elevation view showing the traveling wave tube and the capsule aligning structure.

In Figure 1 a traveling wave tube 11 is shown disposed in a support or capsule member 25. Traveling wave tube 11 includes a cathode 37 heated by means of heater 55 to provide an electron beam, not shown, which beam is focused and directed by a pole piece 33 and by magnetic means of any suitable conventional design, not shown, through a slow wave transmission line structure 13 consisting of an elongated ribbon type helix to impinge on an electron collector anode 19. Coupling means 15 supported by capsule 25 and which may consist of helical windings in concentric relation to helix 13 couples an input electrical signal to the end of the helix 13 nearer the cathode 37. A second coupling means 17, similar to coupling means 15, couples the output signal from the end of the helix 13 nearer the anode 19.

The helix 13 provides a high frequency electrical transmission path through the tube 11 and is designed so that the phase velocity of an electrical wave introduced by coupling means 15 is substantially the same as the velocity of the electron beam projected through the helix 13

30 so that by virtue of the energy interaction with the electron beam, the electrical wave is amplified and coupled out by coupling means 17. Collector anode 19 consists of a tubular metallic member having an open end thereon which is disposed adjacent one end of helix 13 and which is sealed to one end of glass envelope 27.

35 The opposite end of anode 19 is tapered to form a closed end and provides a means to dissipate residual electron energy. The open end of anode 19 is affixed to an elongated tubular envelope 27 which may be of glass or other suitable material. Anode 19 together with envelope 27, sleeve 47 and bulb 49 form an evacuated container within which are located the cathode 37 and beam controlling elements 56 part of which are affixed to base supports 69 and 71. Metallic tubular member 63 provides a magnetic shield for the cathode 37 and the beam controlling elements.

40 Capsule member 25 consists of a partially hollow metallic tubular envelope including member 24 supporting ring member 22 which centrally locate and align anode 19 and envelope 27 within capsule 25. Included

45 within capsule 25 are cooling means 18, insulative supports and terminations, not shown, for input and output coupling means 15 and 17, respectively. Cooling means

50 18, of which only the end portions are shown, may be of any design adapted for cooling a traveling wave tube and may, for example, consist of pipes 18' adapted for passing liquid adjacent anode 19, and of pipes 18'' which direct air along the length of the helix 13 and the cathode 37 portion of the tube 11.

55 The cathode end of the traveling wave tube 11 is shown in more detail in Figure 2. The cathode 37 having an electron-emissive coating on a surface 38 thereof is heated by means of toroidal heater 55 which is wound in a manner to effect more efficient operation, to be described in detail hereinbelow. Accelerating anode 39 is supported by cup shaped support member 41 which is in turn affixed, as by brazing, to a generally disc-shaped

60 65 70 75 80 85 90 95

magnetic pole piece 33. The magnetic pole piece 33 is provided with a centrally located aperture to allow the passage of the electron stream and a protrusion 34 around the aperture which is generally frusto-conical in form. Focusing electrode 43 is affixed to the base supports 69 and 71, not shown in this view.

An electron beam in its path through the helix 13 is characterized by a helical or Brillouin type of flow. To obtain proper helical flow, the electrons produced by the cathode 37 must, prior to entering the helix 13 region, be formed into a beam which enters the helix region at a predetermined point by the accelerating anode 39 and the focusing electrode 43. The electron beam entering the helix 13 passes through an aperture 40 in magnetic pole piece 33 which further effects beam control. The pole piece 33 with its frusto-conical protrusion 34 is useful to provide the proper field conditions, as the beam enters the helix 13 region to obtain the aforesaid helical flow. The beam of electrons is directed through the center of helix 13 which, as above noted, is disposed along the length of the tube 11 and supported within envelope 27 by quartz, or the like, tubular support 29. Attenuating material, not shown, necessary for proper operation of the traveling wave tube as an amplifier may be disposed on the exterior wall of the quartz tubing 29. Helix 13 is aligned with aperture 40 by inserting the helix and the enclosing support 29 into snug fit with an open end section of a helix base support 31 which is centrally affixed to a reference surface on the same side of magnetic pole piece 33 as the frusto-conical protrusion 34 as by spot welding.

Initially, and as will be discussed in detail subsequently, the helix 13 is centered and aligned at the end adjacent the cathode 37 and then the helix 13 and the helix containing tubular envelopes 27 and 29 are inserted into capsule 25 and the anode 19 end of the helix 13 is constrained and aligned by ring member 22 and support member 24. Since the tube 11 is intended for high power operation, very accurate alignment of the axis of the helix 13 with the axis of the electron beam is necessary, otherwise electrons impinging on the helix may cause undesired hot spots on the helix, thus undesirably affecting proper operation of the tube.

The assembly of the cathode end of the tube, in order to provide coincidence of the axes of the cathode 37, accelerator 39, pole piece 33, and helix 13 is next to be described. As may best be seen in Figure 5 a cylindrical metallic sleeve 47 having an accurately machined ring-shaped shoulder member 48 affixed to the inner wall thereof, is itself vacuum sealed to the glass bulb 49. Shoulder member 48 serves as a reference surface for positioning the cathode 37 and the pole piece 33. An accurately machined ring-shaped member 36 is affixed to the external wall of the tubular envelope portion 47 to be in coincidence with pole piece 33 and, in fact, does form part of the pole piece 33 magnetic structure. The surfaces of member 36 serve as reference surfaces for affixing and aligning the tube 11 within capsule 25 as will be detailed hereinbelow.

The cathode 37 subassembly which, as shown in Figures 1 and 2, includes focusing electrode 43, heater 55 and support members 54 and 62 is initially mounted as a unit onto glass base 49' through supports 69 and 71 which are affixed to pin members 73 and 75 which are in turn vacuum sealed to glass base 49'. To position the cathode 37 subassembly within bulb 49 a cylindrical jig 65 (Figure 5) conformable to sleeve 47 and having a center rod extension 67, is inserted in sleeve 47 to bear against shoulder 48 in an accurately formed fit.

The cathode 37 subassembly is inserted in bulb 49 and centrally disposed aperture 45 in cathode 37 receives the rod 67 thereby aligning the cathode 37. A stop 68 carried by rod 67 locates the focusing electrode 43 and the cathode 37 a predetermined desired distance from

shoulder 48. The base 49' is then sealed onto bulb 49 and the cathode 37 subassembly is thus located in position. Jig 65 is then withdrawn.

Referring again to Figure 2, the pole piece 33 having accelerator electrode 39 and support 41 affixed thereto is next fitted into the metallic sleeve 47 and affixed to shoulder member 48 as by screws 50. The pole piece 33 also has affixed thereto a helix base member 31 which is of cylindrical construction having a reduced or step section 30 against which helix support 29 butts. Base member 31 is affixed in coaxial relation with the truncated cone 34; helix 13 having previously been attached as by spot welding to said base member 31. Quartz tubing 29 is then slipped over helix 13 and into a snug fit with base member 31.

The outer glass tubing 27 is affixed to cup shaped flange member 35 which member is formed to provide accurate mating surfaces with relation to the pole piece 33 and with sleeve 47. Glass tube 27 is next slipped over quartz tubing 29 and tubing 29 is supported by a shoulder 26 on anode 19 so as to be in predetermined spaced relation from tube 29 along the entire length thereof, Figure 1.

Referring to Figure 6, the collector anode 19 end of the helix 13 is positioned to have the beam axis and the helix axis coincident by inserting the tube 11 within capsule 25 and affixing, as by screws 52 (Figure 2), member 36 in recessed portions 28 and 40 which are formed to receive member 36 in conforming relation therewith. The anode 19 is inserted through ring member 22 in support 24 and constrained into alignment with the cathode end of the helix and the beam axis cup shaped flange member 35 being sufficiently flexible to permit this alignment. The two opposite ends of helix 13 are thus accurately aligned with the axis of the electron beam provided by cathode 37.

To obtain optimum operation of a traveling wave tube, the electron beam should be uniform in cross section. For this purpose, I provide the cathode 37 having a concave surface 38 which tends to direct the electrons toward a common center point. The inherent mutual repulsion characteristics of the electron beam is thus partially compensated for, and a more uniform cross section beam results. Further, cathode 37 is provided with a recess 51 which is formed such that the outer portions of cathode 37, and in particular the outer edges thereof, obtain from heater 55 a larger supply of radiated heat. Due to the larger mass of metal in these outer portions good heat conduction is obtained so that no portion of the cathode can be appreciably hotter than any other portion. Since the outer portions of cathode 37 are also subject to more heat losses due to radiation of heat to adjacent elements and due also to the fact that the outer portions have larger heat radiating surfaces, the additional supply of heat is required to maintain a uniform temperature throughout emitting surface 38 so that an electron beam of uniform cross section can be provided.

I have found that the cathode heaters heretofore used, develop magnetic fields in the beam forming region which adversely affect the electron beam. To correct for the above, I provide a novel cathode heater which provides the necessary heat to the cathode but does not adversely affect the electron beam.

To provide a proper heating effect throughout the cathode 37, the heaters should be spaced from other elements and should preferably be self-supporting since any materials used to support the heaters will cause an increase in the amount of desirable gases introduced into the tube.

In Figure 3, there is shown an air core toroidally wound coil 55 in accordance with my invention. A first lead 53, supported by insulative member 54, Figure 2, is connected to coil 55. From the point where the lead 53 is connected to the coil, a first portion 57 of the

coil is wound in a left hand sense or clockwise direction, and a second portion 59 of the coil is wound in a right hand sense or counter clockwise direction. A second lead 61, also supported by member 54, Figure 2 is connected to the coil at a diametrically opposite point from the first lead 53. The two portions 57 and 59 of the coil 55 are thus wound to have opposing sense and the magnetomotive forces produced by the two portions of the windings are, in a direction as shown by the arrows, in aiding or complementary relation to each other. The magnetic field developed by the coil 55 is substantially confined to the region within the toroidal winding and only negligible external fields are developed. Good support is provided by two leads 53 and 61 which are sufficiently rigid to maintain the toroid 55 a predetermined distance from the cathode 37.

In Figure 4, a portion of the ribbon helix 13 is shown. The helix 13 is made of a ribbon type material in order to provide the greatest amount of heat dissipating surface and for the purpose of presenting the least amount of surface area on which the axially moving electron beam can impinge. Electrons impinging on the helix 13 cause the helix to become heated, which heat may cause improper operation of the traveling wave tube. Since the tube is intended for high power operation, a large number of electrons flow through the helix. The number of electrons which impinge on the helix 13 should be kept at a minimum to prevent the helix 13 from becoming excessively hot. Although the radiating surface is maximized and the area susceptible to being impinged by the electron beam is minimized, due to the large powers involved, the helix still may tend to run hot and even to develop hot spots.

In order to adapt the helix 13 for high power operation, I coat the outer surface 30 of the helix 13 with a material having good heat radiation characteristics, such as finely divided carbon. A carbon suspension may be conveniently applied to the helix 13 as by spraying to provide a coating of uniform thickness. In one practical embodiment, wadding of any suitable material, not shown, is first inserted between the turns of the helix 13 to mask the surfaces on which a carbon coating is not necessary and only the outer surface 30 is coated. Carbon applied to the inner surfaces 32 does not appreciably contribute to the radiation of heat away from the helix 13. Carbon may also be applied between the turns on the sides of the helix, although I found the application of a uniform coating of carbon between the turns to be less convenient than applying the carbon to only surface 30.

The carbon coating on the helix 13 functions as an excellent heat radiator to prevent the helix from developing hot spots and will cause the helix to operate at a low temperature to provide good operating conditions for the traveling wave tube.

While specific examples have been given in describing details of this invention, it will be understood that they have been given merely by way of illustration and that the invention is not limited thereto.

What I claim as new and desire to secure by Letters Patent of the United States is:

1. A traveling wave tube comprising beam providing means and beam controlling means including a magnetic pole piece and a slow wave transmission line affixed at one end thereof to said pole piece, a collector electrode affixed adjacent the opposite end of said transmission line in such a manner as to provide some relative movement between the axis of said collector electrode and the axis of said beam providing means, an encapsulating member for said tube, support means in said encapsulating adapted member to receive said collector, a surface on said encapsulating member accurately disposed with respect to said support means and adapted to abut a portion of said pole piece, said surface and said collector support means constraining and maintaining said beam

controlling means in alignment with said beam providing means.

2. A traveling wave tube, comprising a cathode, a collector anode and an elongated slow wave transmission line disposed along the axis of an electron beam therebetween, means supporting said transmission line, a magnetic pole piece having a centrally formed aperture therein, one end of said transmission line affixed in concentric relation to said pole piece aperture, the opposite end of said transmission line fixed with relation to said anode, said anode being fixed for limited movement with its axis in substantial alignment with the axis of said beam, said magnetic pole piece having bearing surfaces formed thereon, a capsule member, support means in said capsule having a bearing portion adapted to receive said anode, and recessed portions in said capsule accurately disposed with relation to said bearing portion and adapted to receive said pole piece in conforming relation, said anode support means and said recessed portions effecting alignment of the axis of said transmission line and the axis of said beam.

3. A traveling wave tube comprising a cathode, a collector anode, a helix disposed along the path of an electron beam therebetween, a first tubular member snugly encasing said helix, a second tubular member encasing said first tubular member, a magnetic pole piece having an aperture therein, one end of said helix being affixed in concentric relation to said aperture in said pole piece, the opposite end of said helix being held substantially concentric with said aperture by said second tubular member, said pole piece having reference surfaces formed thereon, said second tubular member having one end flexibly affixed to said magnetic pole piece with its axis in substantial alignment with the aperture in said pole piece, a capsule member adapted to contain said traveling wave tube in an axial ring in said capsule adapted to receive said second tubular member and said anode, and recessed portions in said capsule adapted to receive said reference surfaces in conforming relation, said ring and said recessed portions effecting alignment of second tubular member and the said encased helix with the path of said beam.

4. In the assembly of a traveling wave tube including a cathode and a helix, the method of aligning the helix with relation to the axis of an electron beam, comprising positioning a reference surface with respect to the axis of said helix, said reference surface having an aperture in the center thereof, centering the cathode of said tube with the axis of the aperture, positioning the cathode a predetermined distance from said reference surface, affixing the center of the base of said helix coincident with the aperture in said reference surface, encasing said helix in a first tubular member, encasing said first tubular member in a second tubular member, inserting said second tubular member in a support capsule having a constraining support adapted to receive said second tubular member, and affixing said support capsule member to said reference surface.

5. A traveling wave tube adapted for use at high power comprising a cathode, a collector anode and a ribbon type helix disposed along the path of an electron beam therebetween, said helix having only the outer surface thereof coated with a material of high heat emissivity, means aligning said helix with the axis of said electron beam, a wire heater for said cathode, said heater being self-supporting, helically wound and formed in the shape of a torus, said heater having portions thereof wound in mutually opposing senses, whereby external fields produced by said heater are minimized.

6. A self-supporting wire heater for a cathode, said heater being helically wound and formed in the shape of a torus, respective portions of said heater being wound in opposing senses.

7. A self-supporting helically wound wire heater wound on an air core and formed in the shape of a torus,

one helically wound portion of said heater wires wound in a left hand sense and a second portion of said heater wires helically wound in a right hand sense such that magnetomotive forces developed by said heater are oriented in the same relation whereby negligible fields external to said air core are produced.

8. A helically wound wire heater shaped in the form of a torus, said heater having alternate portions of said wires wound in a right hand sense and other alternate portions wound in a left hand sense to prevent formation of external fields thereby.

9. A slow wave structure for a traveling wave tube comprising a ribbon helix having only the outer surface thereof coated with a material of high heat emissivity for dissipating heat energy from said helix.

10. A slow wave structure for a traveling wave tube comprising a ribbon helix having the outer surfaces only coated with a carbon suspension for radiating heat energy from said helix.

11. A traveling wave tube including a ribbon helix, a thin tubular dielectric support for said ribbon helix, said helix having only its outer surface coated with a material of high heat emissivity for dissipating heat energy from said helix.

12. A traveling wave tube comprising a cathode, a collector anode and an elongated slow wave transmission line disposed along the axis of an electron beam therebetween, said transmission line having a coating of a material of high heat emissivity, means supporting said transmission line, a magnetic pole piece having a centrally formed aperture therein, one end of said transmission line affixed in concentric relation to said pole piece aperture, the opposite end of said transmission line adjacent to said anode, an envelope surrounding said slow wave transmission line and affixed at one end to said anode, said envelope having its opposite end flexibly attached to said pole piece, said magnetic pole piece having bearing surfaces formed thereon, a capsule member, support means in said capsule adapted to receive said anode, and recessed portions in said capsule adapted to receive said pole piece in conforming relation, said anode support means and said recessed portions effecting alignment of the axis of said transmission line and the axis of said beam.

13. A traveling wave tube comprising a cathode, a collector anode, a helix disposed along the path of an electron beam therebetween, said helix having the outer surface thereof coated with a material of high heat emissivity, a first tubular member snugly encasing said helix, a second tubular member encasing said first tubular member, a magnetic pole piece having an aperture therein, said second tubular member having one end flexibly fixed to said magnetic pole piece in concentric relation to said aperture, one end of said helix being affixed in concentric relation to said aperture in said pole piece, the opposite end of said helix being held concentric with said aperture by said second tubular member, said pole piece having reference surfaces formed thereon, a capsule member adapted to contain said traveling wave tube in an axial ring in said capsule adapted to receive said second tubular member and said anode, and recessed portions in said capsule adapted to receive said reference surfaces in conforming relation, said ring and said recessed portions effecting alignment of second tubular member and the said encased helix with the path of said beam.

14. A traveling wave tube having an electron gun and a slow wave structure, an envelope enclosing said slow wave structure and said electron gun, said envelope hav-

ing a flexible portion between said gun and said slow wave structure whereby a central axis of each may be tilted relative to the other, a reference surface on one side of said flexible portion, means for aligning the axis of the electron stream provided by said electron gun with the axis of said slow wave structure, said means including an aligning member connected to said reference surface and having a support means adapted to constrain the end of said tube on the opposite side of said flexible connection into alignment with the axis of said electron stream.

15. In a traveling wave tube including an electron stream producing gun and an elongated slow wave transmission line enclosed in an evacuated envelope a reference member external to said envelope and between said electron stream producing means and said slow wave structure, said evacuated enclosure having a flexible section between said electron stream producing means and said slow wave structure, means for aligning the axis of said slow wave transmission line with the axis of the electron beam provided by said electron beam producing means, said means comprising a capsule member positioned around said slow wave transmission line and fixed to said reference surface, means including a support means adapted to receive the end of said enclosure opposite said electron gun and constrain said enclosure and said slow wave transmission line into alignment with the axis of the electron beam.

16. In a traveling wave tube including an electron gun for producing a stream of electrons and an elongated slow wave transmission line, a magnetic pole piece having a centrally located aperture and a reference surface thereon, bulb means enclosing said electron gun and affixed to the reference surface of said magnetic pole piece to align the electron stream and the centrally located aperture in said magnetic pole piece, an envelope member flexibly attached to the opposite side of said pole piece from said electron gun and enclosing said slow wave structure, said slow wave structure being at least partially supported in alignment with the centrally located aperture in said pole piece by said envelope member, means for aligning the axis of said slow wave transmission line and the electron stream provided by said electron gun, said means comprising a capsule member having one end mechanically coupled to said magnetic pole piece in such a manner as to surround said envelope member, said capsule member including a support means positioned internally thereof to support said envelope and constrain said envelope and slow wave transmission line into alignment with the axis of the electron stream.
